[57] CLAIM

The ornamental design for a mobile telephone unit, substantially as shown and described.

DESCRIPTION

FIG. 1 is a top plan view of a mobile telephone unit, showing our new design; the telephone cord is understood to continue uniformly throughout the broken line portions of the several views;

FIG. 2 is a front elevational view thereof;

FIG. 3 is a bottom plan view thereof;

FIG. 4 is a rear elevational view thereof;

FIG. 5 is a side elevational view thereof taken from the right side of FIG. 1;

FIG. 6 is a side elevational view thereof taken from the left side of FIG. 1;

FIG. 7 is a perspective view thereof; and

FIG. 8 is a perspective view thereof with the handset removed.

FIG. 1

FIG. 3

FIG. 5

FIG. 6

FIG. 7
